UNITED STATES PATENT OFFICE.

EDWARD O. ELY, OF BOSTON, MASSACHUSETTS.

BUTTON-STAPLING MACHINE.

SPECIFICATION forming part of Letters Patent No. 363,054, dated May 17, 1887.

Application filed July 14, 1886. Serial No. 207,997. (No model.)

To all whom it may concern:

Be it known that I, EDWARD O. ELY, of Boston, county of Suffolk, and State of Massachusetts, have invented an Improvement in Machines for Supplying Buttons with Staples, of which the following description, in connection with the accompanying drawings, is a specification, like letters on the drawings representing like parts.

- 10 Many kinds of button-setting machines now in common use are provided with buttons having eyes, through which two-pronged staples are passed. In some instances the buttons follow in the raceway, while the staples hang free, 15 and in other instances the staples follow in a raceway, while the buttons hang free; but so far as known to me the buttons have been supplied with or "threaded" with staples by hand.
- 20 This invention has for its object to construct an organized machine for automatically passing a staple through the eye of a button preparatory to the passage of the combined button and staple into a guide tube or chute and 25 then into a detachable tube, the combined button and staple being thereafter taken from the said detachable tube to be attached to a boot, shoe, or other article.

In accordance with this invention two hoppers are provided, from which lead suitable raceways, one of the said hoppers containing staples while the other hopper contains buttons, suitable means being provided for causing the said staples and the said buttons to separately follow along their respective raceways into a guide tube located at the termination of the said raceway, upon which the staples slide, the said guide-tube receiving the said staples, one at a time, as they are dropped from the 40 terminus of the staple-raceway, and a suitable stop or holder being provided for checking the downward movement of the staples within the guide-tube, means being provided for actuating the said stop or holder at determinate intervals.

One side of the guide tube, below the stop or holder for checking the downward movement of the staple, is cut away or recessed to receive the eye of the endmost button in the 45 button-raceway, so that as the lowermost staple is released one of its legs in falling passes

through the eye of the button, then entering the side of the guide-tube, and hence lying in its path of movement.

The face of the guide-tube is slotted its entire length, and, as shown, is bent outward or inclined at its end, so that a staple with its legs pointing downward may pass freely therein, the eye of the button to which the staple is connected following in the slot in the said guide-tube. For a short distance along the under side of the inclined portion of the guide-tube the metal is cut away, so that when a staple not connected to a button arrives at such point the staple may fall out. At the same time the staples connected loosely to the buttons swing out of the guide-tube and assume a vertical position; but in the further downward progress of the button the staple meets a projection, which reverses the position of the staple, the latter entering a continuation of the guide-tube crown foremost, the combined button and staple passing from the said guide-tube into suitable detachable tubes, which hold the said buttons and staples to be transferred to a button-setting machine; but I desire it to be understood that the staples connected to buttons might be fed directly into a button-setting machine without reversing the staples, as described.

Figure 1 shows in top view a machine embodying this invention for supplying buttons with staples, the lids of the hoppers and a portion of the frame being removed; Fig. 2, a side elevation of Fig. 1; Figs. 3 and 4, sectional details of the button-raceway, taken, respectively, on the dotted lines x x , y y , Fig. 2; Fig. 5, a front elevation of a portion of the machine, showing the auxiliary staple chute or tube and a portion of the staple and button raceways and the devices for causing one leg of the staple to pass through the eye of the button; Fig. 6, a right-hand side view of Fig. 5; Fig. 7, a vertical section of Fig. 5, taken on the dotted line x' x' ; Fig. 8, a vertical section of Fig. 5, taken on the dotted line x^2 x^2 ; Fig. 9, a rear side view of the vertically-moving block and its finger for releasing the retaining device for the staple, that the latter may descend and pass through the eye of a button; Fig. 10, a detail to be referred to.

The bed-plate A and frame-work A' mounted

thereon are of any suitable construction, a suitable standard or frame, A², being secured to the frame-work, in which the shafts a'a have their bearings. A plate, a², is secured to the 5 top of the standard or frame A², to the under-side of which are attached two frusto-conical-shaped hoppers, B B', one of which, as B, contains staples, while the other, as B', contains buttons, said hoppers lying side by side and 10 having openings at their smaller ends to receive suitable inclined raceways b b', of such shape in cross-section as to permit the staples and buttons, respectively, to follow therein, the said staples and buttons being picked up 15 by a suitable picking-up mechanism and thrown so as to lodge upon the upper ends of the said raceways.

The picking-up mechanism herein shown consists of a disk, b², attached to the end of 20 each shaft a'a, turning within the rear or enlarged ends of the hoppers B B', said disks having upon their faces suitable tapering curved blades, b³, which, as the disks are rotated by the shafts, pick up a quantity of 25 staples or buttons from the lower portion of the hopper and throw the same off. The buttons picked up by the blades are made to drop upon usual aprons, b⁵, and some of them lodge with their eyes in the groove of the race-way b', the staples so picked falling, some of 30 them, astride the raceway b, made as a ridge or saddle. The raceway b, upon which the staples travel, extends, as herein shown, in a curved line forward, it also being inclined toward the 35 front of the machine. The end of the said raceway b is entered between the walls of a guide-block, c, which serves to guide the staples, the said guide-block c being secured to the tops of the standard or frame C.

40 A guide-tube, c', of sufficient dimension to receive the staples one above the other, co-operates with the guide-block c, (see Fig. 7,) the said guide-tube entering a suitable groove in the face or standard C of the frame, the face 45 of the said staple-chute being slotted to receive the eyes of the buttons, a suitable stop or holder, c², (shown as a spring,) being located at the rear side of the said guide-tube c' to check the downward course of the staples, as shown 50 in Figs. 5 and 7.

A slotted block, d, fitted into a dovetailed groove in the face of the standard or frame C, parallel with the guide-tube, is moved vertically by a wrist-pin, d', carried by a disk, d², 55 secured to a shaft, d³, said disk d² turning in a recess in the standard or frame C, while the wrist-pin d' enters a groove, d⁴, in a block, d⁵, (see Figs. 8 and 9,) secured to the rear side of the slide-block d, said slide-block being cut 60 away vertically at its rear side to receive a bar, d⁶, pivoted at its lower end to the said slide-block d by a pin, d⁷, said bar being also grooved transversely to give sufficient space for the block d⁵.

65 The free or upper end of the bar d⁶, normally acted upon by a spring, d¹⁰, has a finger, d⁸, the

point of which as the slide-block d is lifted is thrown outward or to the left, as in dotted lines, Fig. 7, to pass above the level of the crown of the staple resting upon the step or holder c², and thereafter the finger d⁸ is permitted to move to the right far enough to engage the crown of the staple held by the stop c², and as the block d is made to descend, the said finger, acting upon the crown, causes the 75 staple to be passed below the said stop or holder, the latter yielding for such purpose, but immediately resuming its normal position to check the next staple above it.

The bar d⁶ derives its outward movement by 80 providing the wrist-pin d', which reciprocates the said slide-bar, with a beveled portion, 2, which bears against the stud d⁹, fixed to the rear side of the said bar d⁶ and projecting through the block d⁵, the beveled portion of 85 the wrist-pin as it travels in its circular path acting intermittently against the stud d⁹, causing the pivoted bar d⁶ to rock.

The bottom of the raceway b is grooved for a 90 portion of its length to receive the eyes of the buttons; but on nearing the end the said raceway is cut away or slotted upon one side, (see Fig. 4,) so that the eyes of the buttons may be turned from their vertical position to a right angle, and in this position the eye of the button enters a notch or recess, 3, cut in or across one side of the guide-tube c' a little below the strip or holder c², the head of the button at such time being under the control of a yielding retaining device consisting of a recessed block, 4, supported upon a yielding arm, secured to the standard or frame C by screws 5 5. 95

With the button in the position shown in 100 Fig. 5—viz., with the eye thereof entering the guide-tube—the said eye will receive one leg 105 of the staple as the latter is pushed or moved past the stop c² by the finger d⁸, carried by the slide-block d. Two springs, 6 7, secured to the slide-block d, are arranged to bear upon a button next to the endmost button in the race-way as the slide-block is moved downward, to thus force the endmost button from the yielding retaining device 4 5, and as the said button is forced therefrom the co-operation of the slightly-inclined outer side of the block 4 and the inclined cut-away portion 9 of the guide-tube 110 causes the button then held by the staple to turn partially over, so that the staple may follow down the said guide-tube and the eye 115 of the button follow in the slot in the face thereof. 120

An irregular-notched wheel or mutilated gear, e, is fixed to the shaft d³, and two stiff flat springs, 12 13, secured, respectively, to the raceways b b', are arranged to bear upon 125 the periphery of said notched wheel, to thus serve as an agitator for the raceways, and to better enable the staples and buttons to follow along the same freely. Below its upper end 130 the metal at the lower side of the guide-tube is cut away, as shown in Fig. 7, to permit the free discharge of any staples which are not

connected to buttons, and as the staples which are connected to buttons pass the said open space they swing out and hang freely, assuming a vertical position; but as they reach the 5 end of such cut-away portion the staple strikes the cross pin or bar 16, and its position is thereby reversed as it enters the guide tube again.

To load up a tube for a button-setting machine—such, for instance, as represented in United States Patent No. 328,365—the said tube, as T, (see Figs. 1 and 2,) may be attached by any suitable means to the end of the guide-tube, in order that the staples with connected 15 buttons may be fed directly into the said tubes. In this instance I have shown the shafts d^3 as rotated by a crank, e^6 ; and a pulley, f , is fixed to said shaft, about which passes two belts, $f^1 f^2$, they passing about two pulleys, $f^3 f^4$, 20 mounted, respectively, upon the shafts $a' a'$, and employed to rotate the picking-up mechanism within the hoppers; but it is obvious that any other suitable means may be employed for rotating the shafts. It is also obvious 25 that any other suitable means may be employed to check the downward progress of the staples than that herein described.

I claim—

1. In a machine for supplying buttons with 30 staples, two hoppers and raceways leading therefrom combined with a guide-tube located at the termination of the said raceways, said guide-tube having a staple-receiving passage and a separate slot for the shanks of the buttons, substantially as described.

2. In a machine for supplying buttons with staples, two hoppers and raceways leading therefrom combined with a vertical stationary guide-tube located at the termination of the 40 said raceways, said guide-tube having a staple-receiving passage and a slot for the eye of a button and being notched or cut away at one side to permit the eye of the button to enter it at a point below the delivery end of the 45 staple-raceway, to thereby receive one leg of the staple when it falls, substantially as described.

3. In a machine for supplying buttons with

staples, two hoppers and raceways leading therefrom, and a slotted guide-tube, as described, located at the termination of the raceways, combined with a stop or holder to temporarily check the forward progress of the staples, and with means, substantially as described, to actuate the said stop or holder to 55 release the staple, substantially as described.

4. In a machine for supplying buttons with staples, the hoppers and raceways leading therefrom, and guide-tube located at the termination of the said raceways to receive the 60 combined staple and button, said guide-tube having a hole or opening upon its under side to reverse the position of the staple, substantially as described.

5. In a machine for supplying buttons with 65 staples, the hoppers and raceways leading therefrom, and guide tube located at the termination of the said raceways, the said guide-tube having a staple-receiving passage and a slot for the eye of the button and being notched 70 or cut away at one side to permit the button to enter the guide-tube, combined with a retaining device to retain the endmost button with its eye entering the notch cut in the side of the tube in position to receive a staple, and 75 means for forcing the next button forward, thereby releasing the retaining device and discharging the button retained by it, substantially as described.

6. In a machine for supplying buttons with 80 staples, a raceway to receive the staples, combined with a guide-tube having a staple-receiving passage and located at the termination of the said staple-raceway, said guide-tube being notched or cut away at one side to receive or permit the eye of the button to enter 85 the staple-receiving passage sufficiently to lie in the downward path of the staple, substantially as described.

In testimony whereof I have signed my name 90 to this specification in the presence of two subscribing witnesses.

EDWARD O. ELY.
